[57] CLAIM

The ornamental design for a remote control organizer, as shown and described.

DESCRIPTION

FIG. 1 is a front elevation view of the remote control organizer of the present invention;

FIG. 2 is a back elevation view of the remote control organizer of FIG. 1;

FIG. 3 is a left side elevation view of the remote control organizer of FIG. 1;

FIG. 4 is a right side elevation view of the remote control organizer of FIG. 1;

FIG. 5 is a top plan view of the remote control organizer of FIG. 1;

FIG. 6 is a bottom plan view of the remote control organizer of FIG. 1; and

FIG. 7 is a perspective view of the remote control organizer of FIG. 1, with a remote control unit shown in broken lines for purposes of illustration only and forming no part of the claimed design.
